US00D699091S

(12) **United States Design Patent**
Pelton

(10) **Patent No.:** **US D699,091 S**
(45) **Date of Patent:** **** Feb. 11, 2014**

(54) **KNIFE BLADE INDENTATION**

- (71) Applicant: **DPX Ventures Limited**, Ras Al Khaimah (AE)
- (72) Inventor: **Robert Young Pelton**, Bonsall, CA (US)
- (73) Assignee: **DPX Ventures Limited**, Ras Al Khaimah (AE)
- (**) Term: **14 Years**
- (21) Appl. No.: **29/433,008**
- (22) Filed: **Sep. 24, 2012**

Related U.S. Application Data

- (63) Continuation of application No. 29/413,759, filed on Feb. 20, 2012, now Pat. No. Des. 677,551, which is a continuation of application No. 13/312,965, filed on Dec. 6, 2011.

(57) **CLAIM**

The ornamental design for a knife blade indentation, as shown and described.

DESCRIPTION

FIG. 1 is a left upper perspective view of a knife blade indentation.

FIG. 2 is a right lower perspective view of the knife blade indentation of FIG. 1.

FIG. 3 is a right side view of the knife blade indentation of FIG. 1.

FIG. 4 is a left side view of the knife blade indentation of FIG. 1.

FIG. 5 is a top view of the knife blade indentation of FIG. 1.

FIG. 6 is a bottom view of the knife blade indentation of FIG. 1.

FIG. 7 is a front view of the knife blade indentation of FIG. 1; and,

FIG. 8 is a rear view of the knife blade indentation of FIG. 1. The broken line showing is for environmental purposes only and forms no part of the claimed design.

1 Claim, 5 Drawing Sheets
